UNITED STATES PATENT OFFICE.

CHARLES H. BILTY AND OSCAR C. PETERSON, OF MILWAUKEE, WISCONSIN.

STEAM TURRET.

Application filed June 27, 1927. Serial No. 201,761.

Our invention relates to a combination steam turret more especially intended for use on superheated steam locomotives; the invention having for its object the provision 5 of a steam turret so constructed as to permit a convenient arrangement of the various valves whereby the same may be easily operated from the cab of the locomotive by means of a suitable system of operating rods; while 10 at the same time providing a turret adapted to receive both saturated and superheated steam in separate compartments or chambers and permit the flow of either, or both, qualities of steam, as desired, to the various auxiliaries of a locomotive operated by saturated steam and those operated by a superheated 15 quality of steam.

The invention also has for its object the provision of a turret provided with an emergency shut-off valve for the saturated steam compartment, in order that repair of the various valves in lines leading from the saturated steam compartment may be made should occasion require.

25 The objects and advantages of our invention will be readily comprehended from the detailed description of the accompanying drawings, wherein:—

Figure 1 illustrates our improved turret in 30 side elevation and as applied to a locomotive boiler shell.

Figure 2 is a view taken substantially on the line 2—2 of Figure 1, looking in the direction of the arrows; certain portions or 35 pipes being broken away and shown in section.

Figure 3 is a sectional plan of our improved turret.

Figure 4 is a sectional view taken on the 40 line 4—4 of Figure 3, looking in the direction of the arrows.

Figure 5 is a detail sectional view taken substantially on the line 5—5 of Figure 3, looking in the direction of the arrows.

45 Superheated locomotives that are now coming into use in railroad practice employ front end throttles and have, as one of their chief features, the use of superheated steam for operating various auxiliaries, such as the pump, the electric generator for train lighting, the whistle, the steam coils for train heating, blowers, dynamo for locomotive headlights, etc.; and the usual practice is to 50 employ two separate steam turrets to take care of the various auxiliaries operated by superheated steam as above enumerated and

those operated by saturated steam, as for example the lubricators and injectors.

Our invention consists in providing a single combination steam turret adapted to receive 60 both saturated steam and superheated steam in separate but adjacently arranged chambers or compartments, while at the same time providing an emergency shut-off valve for the saturated steam compartment when occasion 65 for adjustment or repair of the valves in the various steam lines, leading to the saturated steam operated auxiliaries, arises.

Our improved turret comprises a suitable housing 10, preferably consisting of a single 70 piece casting, provided with a flanged base 11 having suitable bolt receiving holes 12 whereby the turret may be properly secured on the boiler shell 13 of the locomotive as shown in Figure 1. The base 11 is provided 75 with an upwardly disposed steam inlet passage or port 14 for receiving saturated steam from a suitable point in the locomotive boiler 13; and this base 11 is provided with a dia- 80 phragm or transversely disposed partition 15 having port or opening 16 therethrough, which is controlled by what is known as a master valve 17 provided with hand-wheel 18 for manual operation. In order to provide for easy manipulation of the valve, the dia- 85 phragm 15 and likewise valve 17 with its operating stem and hand wheel 18, are shown ar- 90 ranged at an inclination in order that the hand wheel 18 may be disposed rearward to- 95 ward the engine-cab. The partition or dia- phragm 15 in reality is a part of the main 100 bottom wall 19 of the saturated steam receiv- ing chamber 20. The housing is preferably elongated laterally into the somewhat rec- tangular form shown in Figure 2 in order 105 to provide a suitable saturated steam receiv- ing chamber 20 permitting the requisite num- ber of connections to be made therewith for operating the various auxiliaries operated by saturated steam.

The top wall 21 of the steam chamber 20 is preferably also shown disposed at an incli- 110 nation, in parallel spaced relation with the bottom wall 19; and at a point in alignment with the valve-port 16, is provided with a tapped opening to receive the threaded base 22 of the valve-stem sleeve member 23 pro- vided with a transverse wall 24 having an in- 115 ternally threaded hub to receive the threaded portion 25 of the valve-stem. The guide 110 member 23 is shown tapering toward the top and externally threaded to receive the pack-

ing-nut 26; the guide member 23 having an apertured diaphragm 27 slightly beneath the immediate upper end, for guiding the valve-stem and to retain suitable packing.

5 The saturated steam chamber 20 at opposite ends is shown provided with tapped openings to receive the conduits or pipes for conveying steam to the auxiliaries operated by saturated steam, as for example the lubricators and injectors of the locomotive. These conduits or pipes are shown provided with the valves 28, 29, respectively, whereby the flow of steam to the respective auxiliary is controlled.

15 It is apparent from the construction thus far described, that in the event repair in either of the steam lines controlled by valves 28, 29, or in the valves themselves, becomes necessary, it may be readily accomplished by 20 closing the master valve 18. The valve 18 is normally open when the locomotive is in operation, so that saturated steam may flow to the injectors and lubricators which are supplied by the lines having valves 28 and 29.

25 The upper part of the turret is also chambered throughout its length to provide a superheated steam receiving chamber or compartment 30. In order to accommodate the master valve 18 and permit its proper and 30 desired positioning, the turret is shown with an overhanging portion 31 shown preferably of arcuate formation, see Figure 3. This portion 31 is also chambered and constitutes a portion of the superheated steam receiving 35 chamber 30, which receives superheated steam through the forwardly presented inlet nipple 32 to which the superheated steam pipe 33 is suitably connected; the pipe 33 leading to a suitable valved connection arranged at 40 the forward end of the locomotive. With the upper part of the turret formed to provide the elongated superheated steam chamber or compartment 30, a plurality of outlet ports are possible to receive the varying sized outlet pipes, as for example shown at 34, 35, 36 45 and 37, whereby superheated steam is conveyed to the various auxiliaries operated with superheated steam as hereinbefore stated. The various lines or pipes 34, 35, 36 50 and 37 are each provided with suitable valves located adjacent to the turret, so that each may be independently controlled; certain of these valves with hand-wheels being shown at 38, 39 while other valves, as for example 55 valves 40 and 41 are shown provided with extensions or rods 42, 43 having suitable operative connection with the respective valve-stems. These rods 42, 43 extend rearwardly into the cab 44 of the locomotive where they 60 are rotatably mounted in a suitable bracket, as at 45, and their free ends provided with hand-wheels as shown in Figure 1 to enable easy operation of the valves when occasion requires. It is obvious that all of the valves of 65 the auxiliary supply lines may be controlled

by suitable rods leading into the cab; the emergency shut-off valve 18 being preferably operated as shown.

It is apparent that with our improved turret any desired number of outlets may be 70 provided in the saturated steam compartment and in the superheated steam compartment for operating the various auxiliaries; and that the valves of the various outgoing lines or pipes will all be located at a convenient 75 point relative to the locomotive-cab.

It is essential to employ saturated steam for the operation of certain auxiliaries because of the condensation or moisture necessary for the lubricators and the injectors; 80 while on the other hand our improved turret with the adjacently arranged steam compartments or chambers helps to maintain the temperatures of the two qualities of steam and therefore likewise reduces the degree of condensation heretofore encountered and therefore provides for greater efficiency.

We have illustrated what is believed to be the best embodiment of the invention, but modifications may be made without, however, 90 departing from the spirit of our invention.

What we claim is:-

1. A steam turret comprising a casing provided with separate chambers, each having inlet and outlet ports, the inlet of one chamber 95 having connection with the saturated steam portion of an engine while the inlet of the other chamber has connection with the superheated steam portion, a master valve mounted in said casing for controlling the inflow of 100 saturated steam, and valves for separately controlling the steam outlets from both chambers.

2. A steam turret for locomotives comprising a single casing provided with separate 105 chambers arranged parallel with each other and having a single separating wall therebetween, the lowermost chamber having a downwardly disposed inlet connected with the saturated steam portion of the locomotive while 110 the other or upper chamber has an inlet connected with the superheated steam portion of the locomotive, a master valve mounted in said downwardly disposed inlet of the casing 115 for controlling admission of steam into the saturated steam chamber, each of said chambers being provided with a plurality of steam outlets.

3. A steam turret for locomotives comprising a single casing having a flanged base for 120 attachment to a locomotive boiler-shell and provided with a saturated steam inlet through said base, a valve in said inlet, said casing above the base being provided with a pair 125 of elongated chambers arranged in parallel relation, one above the other, a superheated steam inlet at top of the casing for admitting superheated steam in the upper chamber, and independently controllable outlets in each of 130 said chambers.

4. A steam turret for locomotives comprising a casing provided at the bottom with a flanged hub for attachment to a locomotive boiler-shell, a saturated steam inlet passage 5 through said hub, a valve operable from above said casing and located in said passage for controlling said inlet, a pair of elongated steam chambers arranged in parallel juxtaposition one above the other, the lower chamber constituting a saturated steam chamber while the other or upper chamber constitutes a superheated steam chamber, both chambers having a plurality of steam outlet pipes connected therewith, valves for separately controlling said outlet pipes, and a superheated steam conduit leading from the front end 10 throttle of the locomotive and connected with said superheated steam chamber.

5. A steam turret for locomotives comprising a casing provided with elongated chambers arranged one above the other, a flanged hub centrally located on the bottom for attachment on a locomotive boiler-shell and ported to admit saturated steam into the lower 25 chamber from the saturated steam space of the boiler, a master valve located in the casing for controlling the admission of saturated steam, a flanged hub connected with the upper part of the casing for admitting superheated

steam into the upper chamber, both chambers 30 being provided with a plurality of outlet valved conduits connected with the various outlets, and means whereby the valves of said conduits may be controlled from the cab of the locomotive.

6. A steam turret for locomotives comprising an elongated casing having a horizontally disposed partition intermediate of the top and bottom walls thereof whereby a pair of steam chambers are provided in parallel relation with each other, said chambers being provided with a plurality of outlets, the bottom of said casing having a flanged hub for attachment to the locomotive boiler-shell, said hub constituting a saturated steam inlet com- 40 municating with the bottom chamber, a master valve in said casing for controlling said inlet, a flanged hub on the upper part of the casing formed to provide a superheated steam inlet communicating with the upper chamber, outlet conduits leading from the various outlets of said chambers, each conduit having a separately controllable valve, and means connected with the valves of the superheated steam outlets and operative from the cab of 45 the locomotive.
